TEMPERATURE MEASURING SPOON

Lester Brown, Flushing, and Frederick J. Burg, Bellerose, N.Y., Robert Dziekonski, Fort Lee, N.J., and Michael Lax, New York, N.Y., assignors to Salton, Inc., Bronx, N.Y.

Filed Oct. 10, 1972, Ser. No. 296,035

Term of patent 14 years

Int. Cl. D10—04

U.S. Cl. D7—50

Fig. 2

Fig. 3

Fig. 4

Fig. 5

Fig. 6

FIG. 1 is a top plan view of a temperature measuring spoon embodying our new design.

FIG. 2 is a side elevation view.

FIG. 3 is a bottom plan view.

FIG. 4 is an elevation view in section taken along line 4—4 of FIG. 1.

FIG. 5 is a slightly enlarged end view taken along line 5—5 of FIG. 1.

FIG. 6 is a slightly enlarged end view taken along line 6—6 of FIG. 1.

We claim:

The ornamental design for a temperature measuring spoon, as shown.
